Paper Polishing Mach.

N^o Patented Nov. 6, 1832.

Cyrus H. Smith and Thomas French, of Ithaca, N. Y.,

Letters Patent

The Schedule referred to in these Letters Patent and making part of the same containing a description in the usual Patent Office style of the invention, of this improvement in the machine for pressing Paper called the "cylinder hot or cold Press."

To all to whom these presents shall come.

Where it is known that Mr. Charles H. Smith & Thomas French both of Ithaca in the County of Tompkins and State of New York, have invented a new and useful improvement in the art of Paper making and that the following is a full and exact description of the construction and operation of said machine as invented or improved by us. - the use and object of this machine, which we have designated by the name of the "Cylinder hot or cold Press" and to press the paper after it is sized and dried & also paper after it is finished, obviating the necessity & labour of pressing each sheet between two press papers, and by placing two or more plates between two or three pieces of paper and press papers, which has been the former mode of pressing paper by hand.

The machine consists of two or more cylinders (2) made long between of steel and six inches in diameter, represented in the annexed drawing, formed of wrought or cast metal, either iron brass copper or composition turned and finished in the most perfect manner and cast or wrought hollow that they may be heated by heat or by steam. These two cylinders are placed one directly above the other and are joined better or bound so that the surfaces shall now the same. The base (4.) of the under cylinder is placed stationary. The upper cylinder is weighed down on the under one by a lever (5) crooking over the upper board (11) to the end of which a rod of substance. The rod is attached to a lever (6) below and has a board at the end containing weights to make the pressure below, the cylinders by which the paper is pressed. The feeding table, a round or roundish collar (8) which augured from the cylinders by an interior bats wheel (10) so as to carry the sheet of paper something lower than

X

surface of the cylinder, money which carries the paper under from Rollers (C) keeps the wheel perfectly smooth when running the pressing cylinders (B) However the necessary wheel (B) which rotates around the Rollers which are ground from the cylinders by an intermediate wheel so as to carry the wheel faster than the surface of the cylinder money into a box (E) - The rotation is, therefore, so as to give the cylinder from the slow to nearly revolutions per minute.

The wheel of black on the feeding table (A) and from under from Rollers (C) which keeps it smooth when running the pressing cylinders (B) thereon on a sloping table (B) which carries the wheel into a box (E) when they are broken and as occasion requires - The foregoing is a description as to dimensions of the cylinder hot and cold press" now operating in the fall creek paper mill, Ottawa & which press from twenty to thirty rooms per day ... it is propelled with gearing and belts attached to the water wheel shaft.

All the cylinders are turned and polished perfectly round and smooth it will obtain the property of throwing paper in the usual manner and thus are very good items of labour and expense in finishing paper

It will also greatly improve the quality of paper both in body & surface
fibres
